UNITED STATES PATENT OFFICE.

FRANK McCARROLL, OF DALLAS, TEXAS.

RUNNING-GEAR FOR AEROPLANES.

1,097,816.

Specification of Letters Patent.

Patented May 26, 1914.

Application filed May 12, 1913. Serial No. 767,008.

To all whom it may concern:

Be it known that I, FRANK McCARROLL, a citizen of the United States, residing at Dallas, in the county of Dallas, Texas, have 5 invented certain new and useful Improvements in Running-Gears for Aeroplanes, of which the following is a specification.

This invention relates to supporting devices for flying machines, and has particular reference to a running gear for aeroplanes.

As at present constructed, aeroplanes of the several different types are necessarily provided with landing devices or so-called 15 "running-gears" for supporting the frames of the machines above the ground, and for permitting safe and gradual landings of the machines. In the case of the running gears which are wheel supported, the machines can run along the ground in starting until a suitable momentum has been attained for elevating the machine, and, in alighting, a gradual stop can be made after the machine has reached the ground. However, as important as these running gears 25 are on a machine in landing and starting, they are a useless factor and detrimental appendage, once the machine has risen into the air, and little attention has been paid 30 to them in their relation to the final efficiency of the aeroplane. In almost every case, the running gears are rigidly depending structures, of such bulky and cumbersome construction, that they create a great 35 head resistance, or, in order to avoid the last mentioned objection, are made so light and inefficient as to render them dangerous for use as alighting devices.

It is the object of the present invention to 40 provide a running gear for aeroplanes which is so disposed that the gear can be put out of sight, and thus out of the path of movement of the aeroplane, after the machine has arisen from the ground, so as to reduce 45 the head resistance of the moving body to a minimum.

It is also an object to construct an aeroplane running gear of the type mentioned 50 which can be raised out of the way, that is from a position below the machine to a position into the frame thereof, without disturbing in any appreciable degree the equilibrium or unduly shifting the center of gravity. This is especially to be avoided 55 in a machine which is flying through the air, and it is always while the machine is

flying that it is desired to dispose of the running gear.

It is likewise an object of the invention to provide a running gear which is readily 30 and quickly drawn out of the wind and is always under the operator's control, both for raising and lowering the gear, and it is furthermore the object to construct the running gear operating mechanism in such 35 operative relation to the engine and operator that it may be actuated either by the engine or manually.

A further object is to provide a running gear which is possessed of all the requisite 40 strength for a safe landing while still having sufficient resilience and flexibility to insure an easy stop without jarring the machine and occupants. And, also, it is an object to provide a running gear which has 45 few parts, is easily assembled, and having the first mentioned requisites, can be readily dismantled from the machine when it is desired to free the machine of all extra 50 paraphernalia for racing purposes, or similar 55 occasions.

With the objects as stated in view, the device will be hereinafter fully set forth and described, reference being had to the accompanying drawings, in which,

Figure 1 is a side elevation of a portion of an aeroplane, showing my improved running gear applied thereto, Fig. 2 is a sectional elevation on the line 2-2 of Fig. 1. Fig. 3 is a detail view of the wheel supports or springs, and Fig. 4 is a detail view of the actuating mechanism for raising and lowering the running gear. Fig. 5 is a front view of Fig. 4.

Referring now more particularly to said 95 drawings 1 denotes the upper longitudinal members and 2 the lower longitudinal member or beam of the frame or fuselage of an aeroplane of the monoplane type, the fuselage being a tubular structure triangular in 100 cross-section and so arranged that the apex of the triangle is lowermost. Ordinarily, the fuselage is suitably covered, as indicated at *a*, with the exception of the necessary pockets or openings for the entrance of the 105 wheels of the running gear, as will hereinafter appear. Behind the engine, which is not here shown, and in front of the driver's seat *b*, is located a chamber *c* below which the running gear is suspended and in which 110 the actuating gear is mounted and into which the wheels are adapted to swing. Said

chamber *c* is suitably located between two of the vertical bars or braces 3, and, in the machine now constructed, occurs about three feet from the front end of the monoplane. 5 This distance, of course, will vary with the machine to which the gear is applied, is determined by the center of gravity of the machine.

10 Mounted substantially in the same angular relation to the beam 2 as the brace-bars 3, are the uprights 4, whose upper ends are suitably secured to the cross-bars 5, which span the aforementioned brace-bars 3. The lower ends of said uprights 4 are carried 15 by the beam 2, and in this manner, the outlines and supporting frame of the chamber *c* are formed.

Spanning the beam 2 and overlapping the lower ends of the uprights 4 is a yoke 6, 20 which is or may be bolted to the frame or fuselage through said beam or bar 2 and the uprights 4. Said yoke 6 is provided with trunnion arm 7, to which the spring arms 8 of the running gear are journaled. The 25 bearing opening in the ends of the arms 7 extend longitudinally so that when the bearing spindles of the spring arms 8 are journaled therein the latter are pivotally mounted to swing upwardly and downwardly laterally of the machine. Said spring arms 8 are peculiarly constructed to serve their 30 present purposes, as will be best seen in Fig. 3. A continuous sheet of narrow strip metal is bent upon itself in three laps, as follows: 35 Beginning at the inturned end 9, the strip extends substantially horizontally as at 10, to begin the formation of a socket, as will appear. Turning upwardly at approximately a forty-five degree angle, the strip is 40 carried up as the leaf or member 11, to the desired length of the spring arm, and is then looped downwardly and back upon itself to form the eye or bearing 12. The leaf or member 13 then continues downwardly along 45 the leaf or member 11, follows around the portion 10, over end 9. It is then turned back over end 9 as portion 9' and carried as 50 leaf 14 to the upper side of leaf 11 and is continued as far as desired or needed to give the requisite strength to the arm. A wedge-shaped space 15 is thus formed at the lower end of the spring arm 8, into which the suitably formed end of a wheel spindle 16 is 55 projected and secured, as by bolt 17 the end 9 and the overlapping leaf portion 9' being drilled to form a socket therefor. It is evident that the spring arm construction is not limited to three laps of the metal, as shown, but that any suitable or required number 60 of laps may be employed, and it is likewise evident that the socket and spindle construction may be varied from that shown in shape and manner oflapping the several portions of the metal strip.

65 Suitable wheels, 18, as, for instance, wire-

spoked motor vehicle wheels, are mounted on the spindles 16, and, when the spring arms 8 are fixed in the solid line position of Fig. 2 in the manner hereinafter described, said wheels, together with the skid 19, support the aeroplane above the ground in position for instant flight. Said skid 19 consists of a tubular member having the rear end thereof attached to the beam 2 at a point in the rear of the chamber *c* and preferably at the rear of the driver's seat, and extending therefrom to a point below the propeller 20, when said member curves upwardly and forwardly to form a shoe 21. Brace members 22 extend from said shoe 21 to the upper part of the fuselage and are connected to the bars or beams 1. They are further connected by a cross bar extending each side from the member 2. Said skid thus supports the forward weight of the machine and engine on the fuselage. It furthermore prevents damage to the propeller in landing and tends to throw the machine into proper landing position so as to give to the wheels 18 a suitable approach to the ground. Flexibly attached to the front and rear edges of the spring arms 8 and 8', at points near the spindles 16 thereof, are fore and aft bracing cables 23 and 24 respectively, the opposite ends of said cables 95 being carried to and suitably fastened to the members 22 or to the frame. The skid 19 is removably connected to the frame of the machine so that provision must be made for guying the spring arms when said skid 100 is removed, as for racing purposes. Thus, the guy wires 23 are normally fixed to the brace bars 22, but when the latter are removed, the guys are adapted to be suitably connected to the lower bar 2 of the fuselage, 105 the preferred position at that time being indicated in dotted lines in Fig. 1, at 23. Said cables are raised and lowered by and with the spring arms 8 and 8', so that the latter are at all times braced against front 110 and rear strains.

The raising and lowering mechanism for the spring arms consists of certain peculiarly arranged cables and a winding device for actuating said cables. One cable 25 is permanently swiveled to the spring arm 8 at *d*, and extending thence to a pulley *e* in the upright 4, from whence it extends to the drum 26 and is passed therearound with an undershot turn or turns. It is suitably fastened to the drum 26 and then continues to a pulley *g* mounted in the upright 4'. From the pulley *g* the cable passes to and through a second pulley *h* in the spring arm 8' and thence to a suitable fastening near the point 125 *d* or the arm 8. The cable 25 passes through a somewhat similar though opposite course, as follows:—Starting at *d'* on arm 8' it extends through pulley *e'* on upright 4' and from there to the drum 26 by way of the 130

5 pulley *f*. After extending around a second groove of the drum 26, and being fastened therein, the cable passes from the top thereof through the pulley *g*', thence on pulley *h*' in the arm 8 and to the corresponding final fastening on the spring arm 8'.

It will be noted that the bight of cable 25 is wound on its drum section or groove with undershot turn or turns, and that the bight 10 of cable 25' is wound on its drum section or groove with overshot turns. By this arrangement, a single drum can be employed to actuate the arms 8 and 8' simultaneously, whether the desired motion of said arms be 15 up or down. A crank 28 is provided for actuating the drum 26. To raise the arms 8 and 8', and thereby the running gear of the machine into the frame or fuselage the crank 28 is operated by the driver, said crank being disposed in position to be easily reached 20 from the driver's seat, and thereby the cables, being actuated by the drum 26 steadily and evenly draw the arms upwardly until the wheels 18 swing into the chamber *c* 25 above the cross bars 5, as is shown in dotted lines in Fig. 2. Attention is called to the fact that each cable 25 and 25' in its return from its respective drum section passes over a bearing pulley mounted in the opposite 30 spring arm. In this manner, the spring arms are continually braced in the opposite lateral directions no matter what the positions of the arms, and, when the wheels 18 are resting on the ground, the arms cannot 35 spread by reason of the two transverse chords *i* and *j* of the cables 25 and 25', the spring arms 8 and 8', however, furnishing any necessary resilience or give required of the gear in landing.

40 Any suitable clutch mechanism may be installed in the apparatus for locking the shaft 27 and the drum 26 in the desired positions, either to hold the running gear in raised or lowered position.

45 A preferred form of clutch device is shown in Figs. 4 and 5. The drum 26 is provided with a series of radially extending peripheral notches or key-ways 29, which are adapted to be engaged by the key 30, which 50 is mounted on a transverse shaft 31. Said shaft 31 is suitably carried in gearings (not shown) mounted on the platform of the machine in front of the driver's seat, and is rotatable by means of a foot pedal 32 having 55 link and crank connections with said shaft. A coil spring 33 is mounted on said shaft 31 to normally press the key against the drum 26 in position to engage the key-ways 29, so that the drum will be normally locked. By 60 pressure on the pedal 32 the key will be disengaged from the drum 26 against the action of said spring and the drum can be rotated. Instead of the key 30, a cam or eccentric of suitable form can be mounted on 65 the shaft 31 to engage the key-ways.

A pulley to which a suitable driving connection from the engine, (not shown), may be attached for actuating the mechanism described, can be provided for rotating the drum shaft, instead of the crank 28, and any desired automatic or manual connecting and disconnecting means may be provided for causing the engine to actuate the running gear.

The operation of the present invention has 75 been sufficiently clearly brought out in the course of the description thereof, and no rehearsal of the former is necessary at this time, but it may be further noted that the wheels, as is clearly shown in Fig. 2, are 80 practically placed out of sight in the frame, and that the spring arms 8 and 8' lie close to the under sides of the latter, and, by reason of the mechanism described, even cables 25 and 25' are drawn into the machine. 85

It is clear from the above presentation, that my improved running gear permits a ready and efficient disposition of the landing devices after the machine has risen into the air, and that this disposition of the gear is 90 effected without danger to the machine or without disturbing the equilibrium of the latter. The apparatus is light and effective, and while possessing all the strength necessary to permit even a rough landing of the 95 machine, also possesses such qualities of resilience and flexibility as will render the landing safe and easy to the machine and occupants.

While the preferred arrangement of the 100 cables has been shown and described herein, I do not contemplate the described arrangement as the only one which will answer the purposes of the invention, and other runs of the cables whereby the spring arms are 105 braced, in their lowered positions, against outward lateral spreading, and are adapted to be raised and lowered by the same cable may be used within the limits of my invention.

Having thus described my invention, what 110 I claim and desire to secure by Letters Patent of the United States is:—

1. A running gear for aeroplanes, comprising in combination with an aeroplane frame, swinging arms mounted on said frame, cables connected to each of said arms and having a variable connection with the opposite arm, and means for actuating said cables to raise and lower said arms, said cables at all times bracing said arms across 120 said frame.

2. A running gear for aeroplanes, comprising in combination with a frame, laterally swinging arms mounted on said frame, cables connecting said arms below and across said frame, and means to actuate said cables and to lock the latter, whereby said arms are raised and lowered or braced against spreading. 125

3. A running gear for aeroplanes, com- 130

1
prising in combination with a frame, laterally swinging arms mounted on said frame, a controlling means in said frame, and cables connected to said controlling means in operative manner to brace said arms against spreading or to raise and lower the latter.

4. A running gear for aeroplanes, comprising in combination with a frame, arms pivotally connected below said frame, controlling means mounted in said frame, wheels carried by said arms, and cables having their ends secured to said arms and their bights passed across said frame and connected to said controlling means in operative manner to brace said arms against spreading and to raise and lower the latter.

5. A running gear for aeroplanes, comprising in combination with a frame, arms pivotally mounted below said frame to have their free ends swing into said frame, controlling means mounted in said frame, and a cable secured by its ends to each arm and having a sliding connection with the opposite arm, each cable also having its bight passed across said frame and operatively connected to said controlling means.

6. A running gear for aeroplanes, comprising in combination, with a frame, a yoke secured below said frame, arms pivotally carried by said yoke to swing laterally upward and project their free ends into said frame, a cable secured to each arm and having a sliding connection with the opposite arm and passing across said frame, and a winding device mounted in said frame and having operative connections with said cables to raise and lower said arms.

7. A running gear for aeroplanes, comprising in combination with a frame, spring arms pivotally connected to said frame, cables connected to said spring arms to prevent said spring arms from spreading laterally in their lower-most positions, and a drum operatively connected to said cables to raise and lower said spring arms at will by means of said cables.

8. A running gear for aeroplanes, com-

prising in combination with a frame, spring arms pivotally connected to said frame and adapted to swing laterally upward against said frame, cables connected to said spring arms to brace them against spreading in their lower-most positions and means for actuating said cables to raise said spring arms out of their lowered positions at will.

9. A running gear for aeroplanes, comprising in combination, with a frame, spring arms pivotally connected to said frame and adapted to swing laterally upward against said frame, cables connected to said spring arms to brace them against spreading in their lower-most positions and means for actuating said cables to raise said spring arms out of their lowered positions at will, said spring arms consisting of a plurality of laps of a continuous metallic strip.

10. A running gear for aeroplanes, comprising in combination, with a frame, spring arms pivotally connected to said frame and adapted to swing laterally upward against said frame, cables connected to said spring arms to brace them against spreading in their lower-most positions and means for actuating said cables to raise said spring arms out of their lowered positions at will, said spring arms consisting of a spring member and trunnion formed of a plurality of laps of a continuous metallic strip.

11. A running gear for aeroplanes, comprising in combination with a frame, laterally swinging arms mounted on said frame, means bracing said arms against fore and aft strain, cables connecting said arms below and across said frame, and means to actuate said cables and to lock the latter, whereby said arms are raised and lowered or braced against spreading apart.

In testimony whereof I affix my signature in presence of two witnesses.

FRANK McCARROLL.
